(57) **CLAIM**

The ornamental design for a three-dimensional sign, as shown and described.

DESCRIPTION

FIG. 1 is a perspective view of a three-dimensional sign according to a first embodiment of our design; and, FIG. 2 is a perspective view of a three-dimensional sign according to a second embodiment of our design.

The broken lines illustrate portions of the three-dimensional sign that form no part of the claimed design. The text in broken lines in FIG. 2 also forms no part of the claimed design.

The three-dimensional sign is suitable to facilitate passenger trips for autonomous vehicles.
